US00D510699S

(12) **United States Design Patent** (10) Patent No.: **US D510,699 S**
Crain et al. (45) Date of Patent: **** Oct. 18, 2005**

(54) **MULTIPLE FUNCTION GEOMATICS POLE SUPPORT DEVICE**

(75) Inventors: **Stephen B. Crain**, Cape Girardeau, MO (US); **Christopher T. Moore**, Creal Springs, IL (US)

(73) Assignee: **Crain Enterprises, Inc.**, Mound City, IL (US)

(**) Term: **14 Years**

(21) Appl. No.: **29/197,219**

(22) Filed: **Jan. 12, 2004**

(51) LOC (8) Cl. **08-08**

(52) U.S. Cl. **D8/395**; D8/354; D8/382; D10/74

(58) **Field of Search** D8/382, 354, 395, D8/390, 339, 394; D3/260; D6/552; D17/22; D26/138; D34/29; 396/419; 248/188.2, 181.1, 177.1, 581, 596; 211/203, 64; 108/147.19, 147.21, 460, 511, 147.15; D10/74

(57) **CLAIM**

The ornamental design for a multiple function geomatics pole support device, as shown and described.

DESCRIPTION

FIG. 1 is a perspective of a multiple function geomatics pole support device showing our new design;

FIG. 2 is a perspective of the underside thereof;

FIG. 3 is a top plan thereof;

FIG. 4 is a bottom plan thereof;

FIG. 5 is a right side elevation, the left side elevation being a mirror image thereof;

FIG. 6 is a front elevation thereof; and,

FIG. 7 is a back elevation thereof.

1 Claim, 5 Drawing Sheets
